US0D1047107S

(12) **United States Design Patent** (10) **Patent No.:** **US D1,047,107 S**
(45) **Date of Patent:** **** Oct. 15, 2024**

(54) **AIR PURIFIER**

(71) **Applicant:** **SHENZHEN PUREMATE TECHNOLOGY CO., LTD.**, Shenzhen (CN)

(72) **Inventors:** **Yiqing Yan**, Shenzhen (CN); **Bo Yang**, Shenzhen (CN); **Shengzhong Zheng**, Shenzhen (CN)

(73) **Assignee:** **SHENZHEN PUREMATE TECHNOLOGY CO., LTD.**, Shenzhen (CN)

(**) **Term:** **15 Years**

(21) **Appl. No.:** **29/849,244**

(22) **Filed:** **Aug. 9, 2022**

(30) **Foreign Application Priority Data**

Jul. 18, 2022 (CN) 202230457516.4

(57) **CLAIM**

The ornamental design for an air purifier, as shown and described.

DESCRIPTION

FIG. 1 is a top and front perspective view of an air purifier showing our new design;

FIG. 2 is a bottom and front perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a sectional view taken along line 9-9 of FIG. 3;

FIG. 10 is a partial enlarged view taken from circle 10 in FIG. 1; and,

FIG. 11 is a partial enlarged view taken from circle 11 in FIG. 2.

The dash-dash broken lines in the drawings depict the portions of the air purifier which form no part of the claimed design.

The dot-dash broken lines in the drawings are included for the purpose of depicting the partial enlarged views.

1 Claim, 11 Drawing Sheets
